UNITED STATES PATENT OFFICE.

ANDREW DALTON, OF MERIDEN, CONNECTICUT, ASSIGNOR TO THE CHAPMAN MANUFACTURING COMPANY, OF SAME PLACE.

DESIGN FOR HARNESS-TRIMMING.

SPECIFICATION forming part of Design No. 14,155, dated August 7, 1883.

Application filed June 11, 1883. Term of patent 3½ years.

To all whom it may concern:

Be it known that I, ANDREW DALTON, of Meriden, in the county of New Haven and State of Connecticut, have invented a new Design for Harness-Trimmings; and I do hereby declare the following, when taken in connection with accompanying drawings and the letters of reference marked thereon, to be a full, clear, and exact description of the same, and which said drawings constitute part of this specification, and represent, in—

Figure 1, a front view; Fig. 2, a transverse section.

This invention relates to a design for harness-trimming, such as rings, buckles, terrets, &c.; and it consists in the ornamentation of the ring, as shown in the accompanying illustration, and hereinafter described.

In illustrating the design I show a terret only. The frame or body of the article is near-

ly cylindrical in transverse section. The outer surface for about half the circumference *a* is plain; the other half or inner surface, *b*, is of little larger diameter than the outer surface, and this inner or largerdiameter portion forms a series of spiral or helical ribs, giving to the inner side of the article a twisted appearance, like a rope. It is this raised twisted or corded ornamentation for the inner surface of the article that constitutes my invention.

What I claim is—

The design for the ornamentation of the body of harness-trimmings, consisting of the plain outer surface, *a*, and the raised corded inner surface, *b*, as shown in the accompanying illustration.

ANDREW DALTON.
